Inventor
Beigh Miller Foote,

Geo. P. Kimmel
Attorney

UNITED STATES PATENT OFFICE

BEIGH MILLER FOOTE, OF MUSKEGON, MICHIGAN

GARMENT-HANGER COVER

Application filed June 10, 1929. Serial No. 369,726.

This invention relates to a cover for garment hangers, and has for its object to provide, in a manner as hereinafter set forth, a cover for the purpose referred to capable of being expeditiously connected in enclosing position with respect to the hanger when supporting a garment, and with the cover formed of a fabric possessing a nap, such as velvet, whereby the garment will be prevented from slipping and held in the position in which it has been originally placed, under such conditions keeping the garment in shape when supported from the hanger.

Further objects of the invention are to provide, in a manner as hereinafter set forth, a cover for a garment hanger which is simple in its construction and arrangement, strong, durable, compact, thoroughly efficient in its use, conveniently installed into position between the garment and the hanger, and comparatively inexpensive to manufacture.

With the foregoing and other objects in view, the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings, wherein like reference characters denote corresponding parts throughout the several views:

Figure 1 is a front elevation of a cover in accordance with this invention and showing the adaptation thereof with respect to a garment hanger.

Figure 2 is a perspective view of the cover.

Figure 3 is a section on line 3—3 of Figure 2.

Figure 4 is a section on line 4—4 of Figure 2.

Figure 5 is a fragmentary view in plan of the cover.

A garment hanger cover, in accordance with this invention includes a flexible body formed of a pair of body sections and a pair of bias pipings which are secured between 50 and project from the top and ends of the

body sections whereby the top and ends of the flexible body will be formed of bias pipings. The body sections and pipings are formed of a nap fabric, such as velvet. As the pipings are set up from bias material the different runs of the nap thereof act to prevent the garment from slipping off. The nap on the body sections also act to prevent slipping of the garment. Each bias piping is of a length less than the length of the combined end and top edges of a body section. Each bias section extends from the bottom of one end edge of a body section to a point between the vertical median and other end edge of such section. The bias piping sections extend in opposite directions with respect to each other.

One of the body sections is indicated at 1 and the other at 2 and each has its lower marginal portion turned to provide a fold 3 secured by a row of stitching 4.

One of the bias pipings is generally indicated at 5 and the other at 6. The bias strips which provide the pipings are folded upon themselves, the folded strips are positioned between and oppose the inner faces of body sections 1, 2. The face edges of the folds of the bias strips are flush with the top and end edges of the body sections. The bias strips and body sections are secured together by a row of stitching 9, in proximity to the edges referred to. The stitching 9 is severed for a portion of its length between the pipings 5, 6 at the portions 7, 8 respectively of these latter to provide an opening 10 to form a passage for the shank 11 of the hook 12 of the hanger 13.

After the bias strips have been secured in the manner as stated to provide the bias pipings the body sections are turned right side out and the cover will be as shown in Figures 1, 2 and 3.

Secured to the inner faces of the body sections 1, 2 near the bottom edges of these latter are snap fasteners 14, 15 for connecting the lower portions of the body sections 1, 2 together for the purpose of maintaining the hanger 13 within the cover. Each snap fastener is formed of two sections of known type. Extending from the sections of each snap fas-

tener is a strap 16 having one end connected to one section of the fastener and its other end connected to the other section of the fastener and said strap 16 provides a loop or support.

5 The straps 16 are employed for the purpose of hanging a lady's skirt or a pair of trousers from the cover.

It is thought that many advantages of a garment hanger in accordance with this invention can be readily understood, and although the preferred embodiment of the invention is as illustrated and described, yet it is to be understood that changes in the details of construction can be had which fall within the scope of the invention as claimed.

15 What I claim is:

1. A garment hanger cover comprising an open bottom body portion, bias pipings extending throughout and laterally from the end and top edges of said body portion, said pipings having spaced parts to provide an opening for the passage of the shank of the hook of the hanger, means carried by the bottom of the body portion for detachably securing the body of the hanger therein, said body portion and pipings formed of fabric of the nap type, and spaced straps depending from said means.

2. A garment hanger cover comprising a body portion formed of a nap fabric and corresponding in contour to that of the body of the hanger, said body portion formed with an open bottom, closed ends and a closed top having a centrally disposed opening for the passage of the shank of the hook of the hanger, said body having its ends and its top in the form of laterally disposed bias pipings, said pipings having spaced parts to provide such opening, and spaced means carried by the bottom of the body portion of the cover for detachably securing the body portion of the hanger within the body portion of the cover.

30 In testimony whereof, I affix my signature hereto.
